PLUNGER FOR PINBALL MACHINES

Nathan R. Glass, Philadelphia, Pa.

Application May 24, 1945, Serial No. 595,614

4 Claims. (Cl. 273—129)

1

This invention relates to an improved plunger for a pin ball machine and braking means therefor.

The primary object of this invention is to provide a plunger that is to be used for a pin-ball machine wherein the playing surface is vertically rather than horizontally positioned in the usual manner.

Another object of the invention is to provide a plunger having means coacting therewith which will retard or slow down the return of the plunger after it has been placed in playing position and released.

With the above and other objects and advantages in view the present invention resides in the novel features of construction, formation, combination and arrangement of parts to be herein-after more fully described, claimed and illustrated in the accompanying drawings forming a part of the present application, and in which:

Fig. 1 is a front view of an embodiment of the invention.

Fig. 2 is a sectional view on the line 2—2 of Fig. 1.

Fig. 3 is a sectional view on the line 3—3 of Fig. 2.

Fig. 4 is a modification of the invention.

Fig. 5 is a sectional view on the line 5—5 of Fig. 4.

Fig. 6 is a sectional view on the line 6—6 of Fig. 4.

Fig. 7 is a detailed bottom view of the actuator.

Fig. 8 is a side view of the braking mechanism for the plunger.

Fig. 9 is a top plan view thereof with the plunger shown in section, and

Fig. 10 is a sectional view on the line 10—10 of Fig. 9.

Referring more in detail to the drawings the numeral 20 designates the ball run of the pin ball machine and 22 the front of the cabinet thereof.

The plunger 24 is mounted in a vertical reciprocating position by means of a depending U-shaped bracket 26 which has the cross member 28 apertured to receive the plunger and the uprights 30 bent at right angles thereto at 32 to be secured to the ball run 20 by fastening means 34. The plunger 24 is provided on one threaded end with a complementary striking tip 36 and on the other end with a knob 38 having a circular rim 40 thereon.

Interposed between the knob 38 and the outer side of the cross member 28 of the U-shaped

2

bracket 26 and in encircling engagement with the plunger 24 is a cushioning coil spring 42.

A coil compression spring 44 which encircles the plunger 24 is mounted intermediate the uprights 30 of the U-shaped bracket 26 and has the lower end thereof bearing against a washer 46 which is retained in place by a cotter key 48 which extends transversely of the plunger 24.

The spring 44 gives the necessary impetus to the plunger 24 to drive the pin ball upwardly along the ball run 20.

Secured to the uprights 30 by any well-known means is a U-shaped plunger guide 49 the cross member of which is apertured to slidably receive and guide the plunger 24.

The plunger 24 being mounted within the interior of the pin ball machine, it is necessary to have means for actuating the plunger placed on the outside of the pin ball machine for operation of the plunger by the player.

The operation of this actuating means will now be described.

Mounted for insertion into an opening 50 in the front 22 of the pin ball machine is a circular front bushing plate 52 having an opening 54 therein to rotatably receive the handle control rod 56, the plate 52 being fastened to the front 22 by fastening means 58.

Secured on the outer end of the rod 56 in contact with the front of the plate 52 is a handle 60 having a grip portion 62 and a circular apertured portion 64 to receive the rod 56, the handle 60 being spot welded to the rod 56 as shown.

Stops 66 struck out of the front of the plate 52 limit the downward and upward motion of the handle 60.

The rod 56 is prevented from longitudinal movement within the opening 54 by means of a cotter pin 68 contacting a washer 70 which contacts the inner end of the plate 52.

The inner end of the rod 56 has a reduced squared portion 72 to receive the apertured end of plunger control bar 74 which is retained on the portion 72 by fastening means 76 entering the internally threaded bore of the squared portion 72 and a washer 78.

The bar 74 and handle 60 extend in opposite directions and at right angles to the rod 56 but they are so positioned that they lie in the same horizontal plane with respect to each other and they are maintained in this position with the handle 60 contacting the lower stop 66 by means of a coil spring 80 one end of which is secured to the plate 52 by a screw 82 and the other end 55 of which is secured to the rod 56 by a screw 84.

The opposite end of the bar 14 has a reduced portion 86 which is adapted to be received in the bifurcated portion 88 of the plunger contacting member 90 which is pivotally mounted on the portion 86 by a pin 92.

The top of the member 90 extends rearwardly of the bifurcated portion 88 and has an upturned end 94 which is adapted to receive an end of the coil spring 96 the other end being secured to the bar 14 by a screw 98. This spring keeps the member 90 in raised position as shown until the plunger knob 38 has been released when it is depressed by contact with the rim 40 until it returns to its normal position again ready for play.

It will be obvious that when the handle 60 is moved upward the plunger 24 will be depressed until the member 90 which contacts the rim 40 loses contact therewith when the plunger 24 will be impelled forward by the action of spring 44 and the pin ball will be put into play. When the handle 60 is moved downward the member 90 will be depressed and will return to its normal position in contact with the rim 40 and the machine will be ready for replay.

In the modification shown in Figs. 4 to 7, inclusive, the plunger 24 is mounted as previously explained for Figs. 1 to 3 inclusive.

The actuating means for the plunger comprises a handle 100 which extends beyond the front of the cabinet 22 and is provided with an upturned end 102 on which is positioned the knob 104. The handle 100 is pivotally mounted between depending brackets 106 by a pivot pin 108 and the upper ends 110 of the brackets 106 are turned at right angles thereto and fastened to the front 22 by screws 112.

The lower ends of the brackets 106 are reduced as shown and bent inwardly at 114 to act as stops for the handle 100. The handle 100 being retained in a horizontal position by means of a coil spring 116, one end of which is received in an opening 118 in the handle 100, the other end of which is secured to the pin ball machine by a screw 120.

Adapted for contacting relation with the handle 100 is a plunger control bar 122 which is pivotally mounted between depending brackets 124 the upper ends 126 of which are bent at right angles secured to the front 22 by screws 128, the bar 122 being pivotally mounted therebetween by means of the pivot pin 130.

As are the ends of the brackets 106 formed so are the ends 132 of the brackets 124 formed, and act as stops for the bar 122. As in the case of the handle 100, the bar 122 is kept in a horizontal position in contact with the handle 100 by means of a coil spring 134, one end of which is secured to the front 22 by a screw 136, the other end of which is received by a pin 138 in the side of the bar 122.

Pivotedly mounted by means of a pivot pin 140 on the bar 122 is the plunger contacting member 142 which contacts the rim 40 of the plunger knob 38.

The member 142 is kept in contact with the rim 40 of the plunger knob 38 by means of a coil spring 144 one end of which is received in the opening 146 in the member 142, the other end of which is received by a pin 148 in the bar 122. A stop 150 provided on the bar 122 prevents the spring 144 from returning the member 142 out of line with the rim 40 of the plunger knob 38.

It will be obvious that when the handle 100 is

depressed the bar 122 will be forced upward depressing the member 142 which in turn will depress the plunger 24 until the member 142 loses contact with the rim 40 when the plunger 24 will be impelled forward by the action of the spring 44 and the pin ball will be put into play. When the handle 160 is moved upward the bar 122 will move downward returning the member 142 to its normal position in contact with the rim 40, the member 142 will be depressed as it passes the rim 40 so that it will return and the machine will again be ready for play.

In Figures 8 to 10 inclusive, there is shown a braking or retarding mechanism 152 for the plunger 24 which is mounted as previously described, and in like manner this mechanism is controlled from the front 22 of the pin ball machine.

In order to accommodate the braking mechanism 152 the plunger guide 49 is provided with an elongated portion 154 which is formed integral with the cross member of the guide 49 and extends at right angles to the plunger 24. The portion 154 is apertured to receive the knurled headed screw 156 therein.

Provided for reciprocal engagement with the portion 154 is the brake member 158, one end of which is recessed at 160 to conform to the shape of the plunger 24 the other end of which is apertured to receive a pin 162 by which the handle 164 is connected thereto. The free end of the handle 166 being screw threaded to receive the adjusting knurled nut 168.

The brake member 158 lies in face to face relation with the portion 154 and reciprocal movement of the member 158 is permitted by an elongated longitudinal slot 170 through which the screw 156 passes, and maintains the portion 154, and brake member 158 in position.

A coil spring 172 which urges the brake member 158 forward in contact with the plunger 24 has one end secured to the portion 154 by a screw 174 and the other end is secured to the brake member 158 by a screw 176.

Thus by adjusting the screw 156 and the nut 168 the amount of pressure upon the plunger 24 can be adjusted by the player.

If no braking effect is desired, the nut 166 can be turned until there is no pressure on the plunger 24. If however the player decides to use the braking mechanism 152 he can control it by permitting full pressure on the plunger and pulling the nut 166 outward as he desires to obtain the desired braking effect.

It will be apparent that there has been provided a plunger control mechanism that will permit actuation of a vertical plunger and also means have been provided for retarding the upward movement of the plunger, and that changes and modifications may be made in the arrangements, combination and proportion of the various parts without departing from the spirit of the invention or extending beyond the scope of the appended claims.

Having thus described the invention, what is claimed as new and desired to be secured by Letters Patent is:

1. A device of the character described for controlling the forward movement of a vertical pin ball plunger comprising a knob on the outer end of said plunger, a rim on said knob, a pivotal lever contacting the rim on the knob on the plunger and adapted to retract the plunger by means of a handle positioned on the front of the pin ball machine.

2. A device of the character described, comprising a vertical pin ball machine plunger, a knob on the outer end of said plunger, a rim on said knob, a control bar pivotally mounted at right angles to said plunger, a control rod pivotally mounted on said bar at right angles to said bar and engaging the rim of the knob at its forward free-end and a handle for controlling said bar pivotally mounted for engagement with one end of said bar at right angles to said rod.

3. The invention as described in claim 2, wherein means is provided for tensioning said bar and said rod to retard the upward motion of said plunger.

4. A device of the character described comprising a vertical pin ball machine plunger, a knob on said plunger, a rim on said knob, a bracket mounted adjacent said plunger, a control bar pivotally mounted in said bracket at right angles to said plunger, a control rod pivotally mounted on said bar at one end thereof, at right angles thereto and contacting said rim of said knob on plunger a spring connected to said rod at the opposite contact end thereof and to

said bar for biasing said rod into contact with the rim on the knob, a spring connected to said bar for biasing said contact end of said rod into contact with the rim on the knob, a bracket mounted in spaced relation to said first mentioned bracket and a handle for said bar pivotally mounted in said last said bracket adapted to contact said bar and thereby control the forward movement of said plunger.
